Primary Examiner — Shawn T Gingrich*Assistant Examiner* — Kathryn Elizabeth Chambers(74) *Attorney, Agent, or Firm* — CANTOR COLBURN LLP(57) **CLAIM**

The ornamental design for a lightbar, as shown and described.

DESCRIPTION

FIG. 1 is a front view of a lightbar showing my new design; FIG. 2 is a side view thereof, the opposite side being a mirror image thereof;

FIG. 3 is a rear view thereof;

FIG. 4 is a bottom view thereof;

FIG. 5 is a top view thereof;

FIG. 6 is a front perspective view thereof; and,

FIG. 7 is a rear perspective view thereof.

The broken lines illustrating portions of the lightbar form no part of the claimed design.
